ATTORNEY

UNITED STATES PATENT OFFICE.

JAMES HOWARD BROWN, OF BALTIMORE, MARYLAND.

SLIDE HOLDER.

Application filed July 16, 1926. Serial No. 122,956.

This invention has reference to a holder for filing glass slides, such as are used by microscopists for the preservation of mounted specimens, sections, smears, etc., the device being also designed for use as a file for photographic negatives, lantern slides, or other flat articles whose surfaces are designed to be protected from scratches, sticking together, etc.

10 The object of the invention is the provision of a device for this purpose which can be cheaply constructed and which will effectively sustain the slides or mounted specimens therein.

15 To the attainment of the above broadly stated objects and others which will present themselves as the nature of the invention is better understood, the improvement further resides in certain novel features of construction, combination and operative association 20 of parts, a satisfactory embodiment of which is disclosed by the accompanying drawings.

In the drawings:

Figure 1 is an elevation of my improvement.

Figure 2 is a sectional view on the line 2—2 of Figure 1.

30 Figure 3 is a fragmentary perspective view to show the manner in which the holders with the specimens therein may be arranged in a filing case.

In carrying out my invention I employ a flat sheet 1. This sheet is preferably of metal but may be formed of card board or any other material suitable for the purpose. The lower edge of the plate is flanged, as at 2, and the body of the plate, at spaced intervals, is slotted longitudinally and transversely and the metal bounded by these slits is bent outwardly to provide ways 3. These ways are arranged in spaced pairs and between each pair of ways there is designed to be received a glass slide, photographic negative or any other plate 4 having specimens, sections, negative or other surfaces which it is desired to preserve and prevent scratching or sticking together. It is to be noted that the flanges 3

that provide the ways terminate a suitable distance above the edge of the plate 1, and the upper edge of the said plate 1, between each 50 pair of ways, is slotted longitudinally, as at 5. The portions 6 of the plate, outward of the terminals of the slits 5, are bent inwardly or forwardly beyond the plane of the flanges or ways 3, and thereby prevent the plates 4 55 from sliding through the ways off of the body 1, regardless of the position which the body is caused to assume.

As disclosed in Figure 3 of the drawings, the body sheets 1 are of a size to be snugly 60 received in the drawer of a filing cabinet and the simplicity of my construction and the advantages thereof will, it is believed, be perfectly apparent to those skilled in the art to which such invention relates so that a 65 further detailed description is not thought required.

Having described the invention, I claim:—

A slide holder of the character described comprising a sheet metal plate having spaced 70 pairs of outstruck guideways thereon arranged in parallel relation, each pair of guideways being adapted to have a flat article slidably engaged therein, one edge of the plate at the ends of all the guideways being 75 formed with an outstanding continuous stop flange adapted for engagement by the flat articles for limiting the movement thereof, the opposite edge portion of the plate being 80 slit at intervals to form tab-like extensions 80 opposite the spaces between the pairs of guideways, the extensions being bent somewhat out of the plane of the major portion of the sheet and engageable with the rear 85 sides of the flat articles for urging them against the overhanging portions of the guideways and thereby preventing looseness, the ends of said extensions being notched 90 out for the accommodation of the operator's fingers whereby they may conveniently grasp 90 the end of the flat article within each pair of guideways.

In testimony whereof I affix my signature.

JAMES HOWARD BROWN.
